UNITED STATES PATENT OFFICE.

JAMES H. WAGENHORST, OF JACKSON, MICHIGAN.

BATTERY-JAR-FORMING MACHINE.

Application filed December 24, 1921. Serial No. 524,647.

To all whom it may concern:

Be it known that I, JAMES H. WAGENHORST, a citizen of the United States, residing at Jackson, in the county of Jackson and State of Michigan, have invented a certain new and useful Improvement in Battery-Jar-Forming Machines, of which the following is a full, clear, and exact description, reference being had to the accompanying drawings.

This invention relates generally to battery jar forming machines and more particularly to certain improvements upon the battery jar forming machine patent to me April 27, 1920, #1,338,470. In that machine the mandrel was turned down to a horizontal position upon the stock and then the stock folded around the mandrel to form the jar. In the present invention the mandrel is supported in a substantially vertical position and likewise the stock and the stock is folded around the mandrel while held in such vertical position, thereby rendering the operation of the device much easier than any of the battery forming machines heretofore devised. Another object of the invention is to provide a mandrel capable of producing a multiple cell battery jar having the plate supporting lugs in the bottom thereof. Another object of the invention is to provide a battery jar having rounded corners in contradistinction from one having square corners. A further object of the invention is to provide a device in which the various operations can be accomplished either by hydraulic or pneumatic pressure and a still further object is to provide a machine which can be used in connection with the liquid form of mandrel capable of producing a multiple cell jar or a mandrel composed of hinged sections such as disclosed in my application filed October 31, 1921, Serial No. 511,859. Other objects will become apparent as the description proceeds.

The invention consists in the novel features of construction and combination, all of which will be fully described hereinafter and pointed out in the appended claims.

In the drawings forming a part of this specification Fig. 1 is a vertical sectional view of a battery jar forming machine embodying my invention, the hinged plates being represented as closed about the mandrel; Fig. 2 is a vertical sectional view on the line 2—2 of Fig. 1, the hinged plates

being shown opened. Fig. 3 is a sectional view on the line 3—3 of Fig. 1, the front plates being open and the side plates closed about the mandrel; Fig. 4 is a detail sectional view on the line 4—4 of Fig. 2; Fig. 5 is a detail sectional view illustrating certain modified forms of hinged plates folded about the mandrel and forming a battery jar with rounded corners; Fig. 6 is a detail sectional view of said plates opened out ready to receive the stock; Fig. 7 is a detail perspective view of one form of mandrel capable of use in connection with my improved machine; Fig. 8 is a detail perspective view partly in section illustrating the form of multiple cell battery jar formed upon said mandrel; Fig. 9 is a detail sectional view showing the manner of overlapping and uniting the front plates.

In the practical embodiments of my invention I employ a main frame 10 which is substantially upright and provided with a back 10^a which is slightly inclined and also a base portion 10^b which is arranged at right angles to the back 10^a and consequently is slightly inclined also. The main frame also comprises a mandrel support 10^c on which the mandrel is supported just before being placed into or removed from the machine. Attached to the back 10^a is a back plate 11 and connected to this back plate 11 by suitable hinges is the side plate 12 and also the side plate 13, which is also connected by suitable hinges, and a front plate 14 is connected to the side plate 12 and a front plate 15 is hinged to the side plate 13. The back plate 11 and the plates 12, 13, 14 and 15 are provided with a supporting ledge or rib 16 adjacent to the lower ends thereof and of a thickness substantially equal to the thickness of the stock from which the sides of the battery jar are to be formed and this stock rests upon this ledge when the plates are opened out as indicated in Fig. 2. The mandrel 17 is preferably composed of a plurality of separate sections 17^a arranged upon a suitable base 17^b and spaced apart, the intervening space 17^c receiving the partition stock to form partitions in the multiple cell battery jar. 18 indicates a mandrel support rigidly bolted to the base 10^b in such position that when the plates 12, 13, 14 and 15 are opened out as shown in Fig. 2 and the stock placed thereon, the mandrel having the partition strips arranged therein can be slid from the

mandrels rest 10^e onto the mandrel support 18 and when in its final fixed position will contact with the stock and press the same against the back plate 11 and then the plates 12, 13, 14 and 15 can be folded about the mandrel so that the stock will be progressively folded about the sides and ends of said mandrel and force out all of the air, thereby preventing the formation of air pockets. The mandrel, besides having the spaces 17^e to receive the partition stock is formed with the recesses 17^a into which the material for the lugs is placed and then before the mandrel is positioned upon the support 18 the piece of rubber stock which is to form the bottom of the battery jar is placed upon the upper end of the mandrel as thus supported. The mandrel support is provided with a clip 18^a at the back of the support and clips 18^b at the sides thereof, which clips 18^b are connected to a bar 18^c which is arranged in a recessed portion of the support 18 and is connected to any suitable form of fluid operated piston by means of which the bar 18^c is moved up and down in order to bring the clips 18^b into or out of engagement with the base of the mandrel. The plates 14 and 15 are provided with off-center tension springs attached to suitable pins mounted on the upper ends of the plates for holding these plates under pressure in either their opened out or their closed positions, their opening movement being limited by the abutting of their rear edge faces against the adjacent edge faces of the plates 12, and 13, respectively.

The two plates 14 and 15 act as folders for the two ends of the margins of the side forming sheet of stock and they also form the side seam as illustrated most clearly in Fig. 9. On these plates I provide a pair of coacting longitudinal blades 14^a and 15^a, respectively, for forming the seams, said blades having a shearing action to trim off the excess from the overlapping edge of the material.

The upper ends of the plates 11 and 12, 13, 14 and 15 are provided with shallow inwardly projecting flanges 11^b, 12^b, 13^b, 14^b and 15^b having concave forming faces for the purpose of turning the edges of the side forming sheet around those of the bottom forming sheet to make the bottom edge seams. For clamping the folded plates together in closed position upon the work, I provide a hand lever 19 hung on a pivot between the arms of a fork 20 and having a hub cam 21 cooperating with a complementary locking member 22 arranged and operating in substantially the same manner as similar parts in my patent previously referred to. As previously stated a piece of stock is placed upon the upper end of the mandrel for the purpose of providing a

bottom to the battery jar; and for the purpose of binding said piece of stock to the mandrel while the jar is being formed I employ a head or plunger 30 carried at the lower end of a rod 31 which works up and down in bearings 10^d constituting a part of the frame and actuated preferably by the fluid operated piston 32 through the medium of links 33 and bail 34, said links and bail constituting a toggle. The up and down movements of the rod 31 are limited by means of a stop 35 adjustably mounted upon the rod and adapted to contact with the bearing portions of the frame. On the edges of the plunger are mounted four downwardly projecting plates 36 for compressing the inwardly turned edges of the side forming sheet which overlap the margins of the bottom forming sheet to constitute the bottom seams, these plates sliding on the edge-turning flanges 12^a, 12^b, etc. The ends of the plunger plates as well as the ends of the edge-turning flanges carried by the side plates meet so as to form complete quadrangles.

In Figs. 5 and 6 I have shown slightly modified forms of plates 11^e, 12^e, 13^e and 14^e, doing away with the plate 15 and it will be noted that each plate is formed with an upwardly curved edge 40 so that when the four plates are folded together as shown in Fig. 5, the stock folded about the mandrel will be given rounded corners as most clearly shown in Fig. 5 and any suitable form of locking mechanism may be employed for binding the parts together.

The work-table 50 can be arranged in advance of the main frame and upon which the mandrels can be placed preparatory to being arranged upon the mandrel rest 10^e just before being introduced into the machine or from which the mandrels with the jar thereon can be placed after said jar has been formed and removed with the mandrel from the machine. By arranging the mandrel and the folding parts in substantially a vertical position, it will be much easier to manipulate the machine inasmuch as the mandrel can be quickly and easily pushed from the rest 10^e onto the support 18 and the stock can be easily arranged upon the opened out plates upon the ledge 16 and then as soon as the mandrel with the partition strips arranged therein is placed upon the mandrel support, the hinged plates can be folded around the mandrel, carrying with it the stock to form the sides and the bottom forming piece with the lugs having been previously arranged upon the top of the mandrel, the plunger can be lowered and the seam forming operations completed.

By arranging the mandrel and the enveloping plates or wings in a substantially vertical position, I overcome the objectionable features of the machine disclosed in

my patent previously referred to. In that machine it was necessary to turn the heavy mandrel from a vertical to a horizontal position and this required considerable strength and the weight of this mandrel upon the stock had a tendency to thin the stock at that point, and in order to overcome this, a thin piece of material had to be inserted between the stock and the hot plate beneath the mandrel. Furthermore, in the machine embodying the horizontal mandrel and the foldable side wings, it was necessary to counterbalance these side wings thereby providing a weighty and cumbersome piece of mechanism. All of these objectionable features are avoided by arranging the mandrel and the enveloping plates or wings in a substantially vertical position and the operation of the machine is rendered much easier in every respect and by having the slidably mandrel in combination with a suitable support provided with clamps, the mandrel is quickly and easily positioned accurately with reference to the foldable members.

While I have shown a hand operated means for opening and closing the plates it is obvious that fluid operated means may be employed if so desired.

It will thus be seen that I provide a simple and highly efficient battery jar forming machine capable of carrying out all of the objects hereinbefore referred to.

Having thus described my invention, what I claim is:

1. In a battery jar forming machine, the combination with foldable means for supporting a sheet of stock substantially vertical and a mandrel contacting with a section of said foldable means, said section of the foldable means being fixed and adapted to maintain the mandrel stationary while the sheet of stock is folded around said mandrel.

2. The combination with a mandrel supported in a substantially vertical position and foldable means for supporting a sheet of stock in a substantially vertical position and in contact with one face of said mandrel and adapted to wrap said stock about said mandrel, the portion of the foldable means in contact with one face of the mandrel being fixed and adapted to maintain the mandrel stationary while the stock is folded around the mandrel.

3. In a battery jar forming machine, the combination with a plurality of substantially vertical plates hinged together, a substantially vertical mandrel support mechanically operated means for releasably locking the mandrel on said support and a vertically movable plunger arranged in alignment with said mandrel support.

4. In a battery jar forming machine, the combination with a mandrel support, of a

mandrel capable of attachment to and detachment from said support, said mandrel being held in substantially vertical position, plunger operated clips for releasably locking the mandrel on said support, a plurality of substantially vertical plates hinged together, said plates being adapted to support a sheet of stock, said mandrel and one of the plates being so positioned with reference to each other as to bind the sheet of stock therebetween, means for folding said plates about the mandrel.

5. In a battery jar forming machine, the combination with a mandrel support, of a mandrel capable of attachment to and detachment from said support, said mandrel being held in substantially vertical position, plunger operated clips for releasably locking the mandrel on said support, a plurality of substantially vertical plates hinged together, said plates being adapted to support a sheet of stock, said mandrel and one of the plates being so positioned with reference to each other as to bind the sheet of stock therebetween, means for folding said plates about the mandrel, and a plunger cooperating with the hinged plates and mandrel.

6. In a battery jar forming machine, the combination with a plurality of substantially vertical plates hinged together, a mandrel support, a mandrel arranged thereon, mechanically operated means for releasably locking the mandrel on said support, said plates being constructed to support a sheet of stock, flanged plates carried at the upper ends of said hinged plates for turning the edges of the stock together with a plunger cooperating with the hinged plates and mandrel and also provided with projecting plates for turning the edges.

7. In a battery jar forming machine, the combination with a main frame having a back, base and mandrel rest, of a mandrel support attached to the base, a plate rigidly connected to the back, a plurality of plates hinged to the first named plate and to each other, a mandrel adapted to be attached to the mandrel support and a plunger cooperating with said mandrel and hinged plates, retaining elements for releasably locking the mandrel on its support, and means for moving said retaining elements toward and away from the support to secure said mandrel.

8. In a battery jar forming machine, the combination with a fixed mandrel support, of a mandrel comprising a base portion and a plurality of spaced sections, clips at opposite sides of said support adapted to engage the mandrel, a connection between said clips, and means for moving said clips toward the support to lock the mandrel thereon, and a plurality of hinged plates arranged substantially vertical and adapted to envelop the mandrel.

9. In a battery jar forming machine, the combination with a main frame having a back, base and mandrel rest, a mandrel support attached to the base, a rigid plate attached to the back and hinged plates connected to said rigid plate, a mandrel comprising a base portion and spaced sections adapted to be connected to the mandrel support, retaining elements for releasably securing the mandrel on said support, means below said support for actuating said retaining elements to secure said mandrel on said support and a plunger cooperating with said mandrel together with means connected to the main frame for operating said plunger.
10. In a battery jar forming machine, the combination with a main frame, of a mandrel support connected to said main frame, a plate rigidly connected to said main frame, plates hinged to said rigid plate, a mandrel adapted to be attached to said mandrel support and be enveloped by the hinged and fixed plate, piston actuated retaining elements for securing the mandrel on the support and a vertically movable plunger cooperating with the mandrel and hinged plates.
11. In a battery jar forming machine, a mandrel support, a mandrel adapted to be arranged theron, a fixed clip for holding said mandrel to the support and movable clips together with means for moving said movable clips.
12. In a battery jar forming machine, the combination with a main frame having a slightly inclined base, a mandrel support attached to said base, a fixed plate and a plurality of hinged plates, a mandrel and a mandrel rest arranged in advance of the mandrel support as set forth.
13. In a battery jar forming machine, the combination with a main frame having a slightly inclined base, a mandrel support attached to said base, a fixed plate and a plurality of hinged plates, a mandrel and a mandrel rest arranged in advance of the mandrel support as set forth, and a vertically movable plunger cooperating with the mandrel and foldable plates and piston operated clips for releasably locking the mandrel on its support.

In testimony whereof, I hereunto affix my signature.

JAMES H. WAGENHORST.
